UNITED STATES PATENT OFFICE.

CHARLES B. ROGERS, OF JOPLIN, MISSOURI.

ROCK CRUSHER.

Application filed September 12, 1924. Serial No. 737,377.

This invention relates to rock crushers, and more particularly to improvements in jaw plates.

In the jaw type of crusher, the work is performed on the lower portion of the jaws and it is the usual practice to reverse the jaws end for end when the lower portions become worn and continue the use of the jaw until the other end portion is worn as thin as possible. The intermediate portion of the jaw receives practically no wear and when the jaws are scrapped, a great deal of the weight of the original jaw must be disposed of as scrap metal at a considerable loss.

In the present invention, I provide jaws or jaw plates which have concaved rear faces, providing thickened portions adjacent each end and a thin central or intermediate portion. This will reduce the weight of the jaws from 20 to 30 per cent, and this reduction is effected on a part of the jaw in which no wear occurs.

In the accompanying drawings, I have shown one embodiment of the invention. In this showing:

Figure 1 is a central vertical longitudinal sectional view of a rock crusher showing the invention applied.

Figure 2 is a transverse sectional view of the movable jaw substantially on line 2—2 of Figure 1,

Figure 3 is a perspective view of a false plate arranged behind the hollowed out portion of the jaw plate, and

Figure 4 is a perspective view of the jaw plate.

Referring to the drawings, the reference numeral 1 designates a suitable support consisting of transverse beams arranged at each end of the machine and adapted to support longitudinal beams 2 on which the machine rests. A stationary, rectangular frame of cast metal encloses the sides and ends of the crusher mechanism and the portion designated by numeral 3 is adapted to receive and support the stationary jaw designated as a whole by numeral 4. As shown, the stationary jaw plate of wear resisting metal is provided with a front face 5 which is substantially flat, and is provided with a rear face 6 that is concave producing a thin central portion. A false plate 7, having a convex face is arranged in the rear of the jaw plate. The false plate is secured to the

frame by means of bolts 8 and is further provided with a rib 9, on the rear side, adapted to enter a groove or recess in the frame 3. The jaw plate is retained in position by means of a lip 10, formed of the false plate and by side members 11 which are arranged on opposite sides of the machine.

A movable jaw support or bumper is mounted opposite in relation to the stationary jaw and consists of a bumper 12 mounted on a shaft 14 and swings thereon by means of an adjustable bearing. The bumper is provided with a jaw plate 16 formed of suitable wear resisting material, the detail construction of which is shown in Figure 4 of the drawings. As shown, it is provided with a rear concaved face 17 and a false plate 18 (see Figure 3) having a convex face, is arranged between the bumper and the jaw plate 16. The jaw plate is retained in position in any suitable manner as by means of a jaw bolt 19, which is carried by the jaw bumper and which passes through a beveled recess or depression 20 in the upper end of the jaw plate. The lower end of the jaw plate is retained in position by means of a toe 21, secured to the jaw bumper by means of bolts 22. A lug 23 is cast on the rear side of the false plate 18 and this lug is adapted to be received in a recess in the jaw bumper (see Figure 2). Stud bolts 24 may also be employed to retain the false plate in position.

The jaw bumper 12 is adapted to be actuated in the usual manner to move it toward and away from the stationary jaw 4. As shown, an eccentric shaft 25 is arranged rearwardly of the jaw bumper 12 and is provided with a pitman 26. Toggle joints 27 are arranged on opposite sides of the pitman. As shown, these toggle joints are provided with rounded ends 28 which are received in bearing members 29, carried by the pitman and having similarly rounded recessed faces. A block 30 is supported on the frame of the machine and is adapted to receive the other rounded end of the rear toggle. A plate 31 is mounted on the rear of the bumper 12 and is provided with a rounded recess to receive the end of the other toggle. A rod 32 is secured to the rear of the bumper and passes through an opening in the rear transverse beam 1. A spring 33 is arranged on this rod between a pair

of collars 34. The rod is threaded and a handle 35 is provided for adjusting the tension of the spring.

In operation, the rotating movement of the eccentric shaft 25 raises and lowers the pitman 26 imparting a reciprocating vertical motion to the inner ends of the toggles 27. This oscillates the bumper and movable jaw back and forth toward the stationary jaw 4. As usual in the jaw type crusher, the lower end of the movable jaw is always nearer the stationary jaw forming a V-shaped crushing chamber and the wear occurs on the lower portion of the jaw plates. It will be apparent that when each end portion of the jaw plate has been worn as thin as possible, and the jaw plate discarded, the loss will be materially reduced due to the fact that a greater percentage of the weight of the material in the jaws is put to the useful work of crushing.

It will be understood that the form of my invention herewith shown and described is to be taken as a preferred example of the same, and that various changes in the shape, size, and arrangement of parts may be re-

sorted to without departing from the spirit of the invention or the scope of the subjoined claims.

I claim:

1. In a jaw-type crusher, a stationary jaw, a movable jaw, jaw plates mounted on said jaws, said jaw plates being provided with flat front faces and concaved rear faces forming an arc of a circle whereby the end portions of the jaw plates are of substantial thickness and the central portions are relatively thin, and means for actuating said movable jaw.

2. In a jaw-type crusher, a stationary jaw, a movable jaw, jaw plates mounted on said jaws, false plates mounted on said jaws at the rear of said jaw plates, said false plates being provided with convex faces forming an arc of a circle, said jaw plates being provided with flat front faces and concaved rear faces adapted to receive the convex portion of said false plates, and means for actuating said movable jaw.

In testimony whereof, I affix my signature.

CHARLES B. ROGERS.
